UNITED STATES PATENT OFFICE.

THOMAS HOUGHTON AND ANGELO D. DICK, OF PHILADELPHIA, PENNSYLVANIA.

IDENTITY-INDICATOR.

SPECIFICATION forming part of Letters Patent No. 475,400, dated May 24, 1892.

Application filed May 2, 1891. Serial No. 391,356. (No model.)

To all whom it may concern:

Be it known that we, THOMAS HOUGHTON and ANGELO D. DICK, citizens of the United States, both residing in the city and county 5 of Philadelphia, State of Pennsylvania, have invented a new and useful Improvement in Identity-Indicators, which improvement is fully set forth in the following specification and accompanying drawings.

10 Our invention consists of an identity-indicator, which is formed of a transparent tube and means for closing the ends thereof, said tube containing a piece of paper or other material on which identification matter is 15 corded, the same being visible through the tube or casing.

Figure 1 represents a side elevation of an identity-indicator embodying our invention. Fig. 2 represents a longitudinal section thereof. Fig. 3 represents a perspective view, the parts being separated.

Similar letters of reference indicate corresponding parts in the several figures.

Referring to the drawings, A designates a 25 casing or tube, which is formed of glass or other transparent material, the same being connected with caps B at the ends thereof by means of a screw C, which is passed through said casing and attached to the caps B. One 30 of the caps is provided with a ring or eye F, whereby the device may be suspended from a watch-chain or other suitable place. Within the casing is a piece E of paper or other suitable material, on which is printed or otherwise recorded the name and address of the 35 owner and any other information desired to be communicated to others in the event of accident to or death of the owner, the piece being rolled so as to be received within the 40 casing and the name and address visible through said casing, owing to the transparent nature thereof. Prior to the assemblage of the parts a quantity of suitable cement is applied to the inner faces of the caps and the 45 ends of the casing are seated in said material, thus hermetically sealing the ends of the cas-

ing and forming water-tight joints between the casing and caps. In the event of an accident or death a person perceiving the indicator obtains therefrom the information as to 50 the name and address of the owner of the device. Should, however, further information be desired, the casing may be broken, whereby access is had to the piece E, which latter may be removed and opened or unrolled and the 55 matter thereon be exposed.

As the ends of the casing are hermetically sealed, should the owner thereof be drowned the entrance of water into the casing, and consequently to the piece E, is prevented, and the 60 device remains intact under such circumstances.

On the inner sides of the caps B are inwardly-projecting cones F, to which the ends of the rod or screw C are secured, and which form 65 grooves in which the ends of the tube are seated, whereby the tube may be centered on the caps, and provision is made for setting the tube true should there be any inequalities in the ends of the tube. 70

In Fig. 3 we show a reverse side of the piece E in dotted lines, so as to expose the name and address side of said piece, said side being visible through the tube A.

Having thus described our invention, what 75 we claim as new, and desire to secure by Letters Patent, is—

An identity-indicator consisting of a transparent tube, separate caps having grooves therein, in which the ends of the transparent 80 tube is seated, a rod within said tube, having screw-threaded ends engaging in openings in said caps, cement in said grooves, hermetically sealing said tube and caps, and a record-piece in said transparent tube, substantially 85 as described.

THOMAS HOUGHTON.
ANGELO D. DICK.
